Charles S. Nelson,
By Wilmarth H. Thurston

ATTORNEY.

UNITED STATES PATENT OFFICE.

CHARLES S. NELSON, OF PROVIDENCE, RHODE ISLAND.

DISH-MOP.

1,150,957.

Specification of Letters Patent. Patented Aug. 24, 1915.

Application filed May 29, 1911, Serial No. 629,992. Renewed April 19, 1915. Serial No. 22,487.

To all whom it may concern:

Be it known that I, CHARLES S. NELSON, of the city and county of Providence and State of Rhode Island, have invented certain new and useful Improvements in Dish-Mops; and I do hereby declare the following specification, taken in connection with the accompanying drawings, forming a part of the same, to be a full, clear, and exact description thereof.

The invention relates to an improved mop for cleaning dishes and the like, and has for its object to provide a mop of this character which will be firmly secured upon its handle and not liable to become disengaged therefrom when in use.

To this end the invention consists of the improved form of dish-mop hereinafter described and claimed, reference being had to the accompanying drawings in which—

Figure 1 is a side elevation of my improved dish-mop in its completed form. Fig. 2 is a side elevation of the handle with the binding wire in position therein. Fig. 3 is a side elevation of a bunch of threads or locks of wool. Fig. 4 is a side elevation showing the bunch of threads secured upon the handle by the first binding operation. Fig. 5 is a side elevation showing the threads in position for the second binding operation. Fig. 6 is a side elevation showing the second binding operation completed. Fig. 7 is a side elevation showing the position of the threads during the third or final binding operation.

Referring to the drawings, 1 represents the handle of my improved dish-mop which is provided adjacent one end with two angular flanges 2 and 3 and an annular concaved groove 4 between said flanges. The end portion 5 of the handle which extends beyond the flange 3 is tapered, all as shown in Fig. 2, and for a purpose to be hereinafter referred to. Extending transversely through the handle 1 at the grooved portion 4 is a hole to receive the binding wire 7, as shown in said Fig. 2. After one end 7' of the binding wire 7 has been passed through said hole 6, and bent down so as to extend beyond the tapered end 5, a bunch of threads or locks of wool 8 are arranged around the handle in the manner shown in Fig. 4, with the lower ends of the threads projecting beyond the end of the handle and the upper portions of the same extending along the handle. With the threads 8 in this position

the other end 7" of the binding wire 7 is wound tightly around the same to form the first winding 9 which binds said threads in the groove 4, as shown in Fig. 4. The upper 60 half of the threads 8 is now drawn down over the winding 9 and the end 7" of the wire 7 is passed through to the exterior of said turned down threads, as shown in Fig. 5. Said binding wire 7 is now wound 65 tightly around the threads 8 at a point adjacent the flange 3 upon the large portion of the tapered end 5 to form the second winding 10, as shown in Fig. 6. A portion of the threads 8 are now drawn back over 70 the winding 10 and the binding wire 7 is wound around the remaining threads at a point adjacent the free end of the tapered end 5 to form a third winding 11, as shown in Fig. 7. The ends 7' and 7" of the binding wire 7 are now twisted together, as shown in said Fig. 7, and the drawn back ends of the threads 8 are drawn down over the winding 11 to complete the mop.

It will be seen that with the above described method of securing the mop upon the handle there are three separate windings at three different points upon the handle, and that the threads forming the mop are securely bound against movement in either 85 direction upon the handle and a very efficient mop is produced.

It will be understood that the last winding 11 may be omitted if desired and a mop of two windings produced.

What I claim as my invention and desire to secure by Letters Patent is:

1. In an article of the character described, the combination, with a handle having a hole extending transversely through the same adjacent one end thereof and an annular flange adjacent said hole, of a bunch of threads arranged around said handle, and a binding wire having one end extending through the hole in the handle and the other end wound around the inner portion of said threads upon one side of said flange and around the outer portion of said threads upon the opposite side of said flange, the two ends of said wire being fastened together upon the interior of the bunch of threads.

2. In an article of the character described, the combination, with a handle provided near one end with an annular groove, a hole extending through said grooved portion, and a tapered end portion, of a bunch

of threads arranged around said handle, and a binding wire having one end extending through the hole in the handle, and the other end wound around the lower portion 5 of said threads to bind them in the groove, the top portion of said threads being then turned down and said end of the binding wire wound around said threads to bind them upon said tapered end portion, the 10 ends of said binding wire being secured together inside the bunch of threads.

3. In a device of the character described, the combination, with a handle having two annular flanges, an annular groove between 15 said flanges, a hole extending transversely through said grooved portion, and a tapered end portion, of a bunch of threads arranged

around said handle, and a binding wire having one end extending through the hole in the handle and the other end wound around the lower portion of said threads to bind them in said groove, then wound around the turned down upper portion of said threads to bind them beyond the outer flange, then wound around the inner portion of said 20 threads to bind them upon the tapered end portion adjacent the free end thereof and then secured to the first mentioned end of the binding wire. 25

CHARLES S. NELSON.
